(57) **CLAIM**

I claim the ornamental design for a saw chain sharpening stone and holder, as shown and described.

DESCRIPTION

FIG. 1 is right side view of the claimed design in association with a housing positioned relative to a saw chain entrained on the nose area of a chainsaw guide bar, shown in broken lines;

FIG. 2 is top view of the claimed design;

FIG. 3 is a left side view of the claimed design;

FIG. 4 is a front view of the claimed design;

FIG. 5 is a back view of the claimed design;

FIG. 6 is a right side view of the claimed design; and,

FIG. 7 is a bottom view of the claimed design.

The broken lines in FIG. 1 are directed to subject matter that forms no part of the claimed design.

1 Claim, 4 Drawing Sheets# US D663,602 S
